PNEUMATIC HAMMERING MACHINE FOR
CLEANING ROLLERS

Willis E. Smith, Springfield, Oreg.

Application April 20, 1948, Serial No. 22,040

6 Claims. (Cl. 15—382)

1

This invention pertains to devices for cleaning surfaces of rollers, and relates particularly to a pneumatic hammering machine for removing adhering particles from the surfaces of rollers such as are used in a kiln or dryer section for the drying of strips of wood veneers.

In the veneer industry, thin sheets of wood cut from green peeler logs are generally subjected to a preliminary drying treatment by passing them over, or between, rolls in a heated chamber in order to reduce the moisture content of the wood. The pressure of the rolls and the elevated temperature of the atmosphere cause the resinous content of the wood to flow, and thus to exude from the surfaces and be deposited upon the rollers. The material decomposes and sets, forming a hard cake which not only increases the diameter of the rolls, but also produces undesirable marks in the surface of the veneers. Heretofore, it was necessary to shut down the drying apparatus periodically and to scrape and chip the hardened mass from the rolls. This procedure is time consuming and therefore expensive, both in added labor costs and in time lost in production while the machine is shut down.

The principal object of the present invention is to provide a device for cleaning a multiplicity of such rollers in one operation with a minimum of attendance and with rapidity and thoroughness.

Another object of the invention is to provide a device for cleaning rollers by means of a tapping and jarring action imparted to the latter by means of pneumatically-operated hammers.

A further object is to provide a roller cleaning device wherein a series of pneumatic hammers are actuated by a valve system operated by the same supply of compressed air.

A still further object of the invention is to provide a roller cleaning device which is light in weight, of simple construction and contains but a minimum number of moving parts, thus insuring long life with minimum repair.

These and other objects and advantages of the present invention will appear from the following detailed description, taken in connection with the accompanying drawings, in which:

Fig. 1 is a perspective view of the swivel attachment by which the device of the present invention is suspended upon, and moved over, the rollers to be cleaned;

Fig. 2 is a fragmentary perspective view of the means for releasably securing the swivel attachment to the cleaning device;

Fig. 3 is a perspective view of the assembled cleaner comprising the present invention;

Fig. 4 is a perspective view illustrating the

2

manner in which the cleaning device is introduced between adjacent and confined rollers;

Fig. 5 is a perspective view, partly in section, showing the cleaning device in operation upon a multiplicity of spaced rollers;

Fig. 6 is a vertical sectional view illustrating the structural features of the device of the present invention; and

Fig. 7 is a perspective view in broken section showing the features of the valve system of the present invention.

The operating mechanism of the cleaning device is housed in a cast body 1 in which four transverse cylinders 2 are formed. Referring particularly to Fig. 6 of the drawing, two of the four cylinders are disposed above the remaining two at a distance approximately the space between the axes of adjacent rollers to be cleaned. Cylinder heads 3 are removably threaded in the exposed ends of the cylinders to define operating chambers. Pistons 4 are slidably received in said cylinders and are provided with piston rods 5 which extend axially therefrom through openings formed in the body 1 and cylinder heads 3 in a line extending through the axis of each cylinder. The exposed ends of these piston rods form the hammers which tap against the rollers to be cleaned.

Extending longitudinally through the body between the upper and lower cylinders is a valve bore 6 which receives the valve assembly of the cleaning device. The valve assembly comprises a valve shaft 7, extending longitudinally through said valve bore, and the offset valves mounted in spaced relation upon the shaft. Referring particularly to Fig. 7 of the drawings, the valves comprise circular sleeves which fit closely about the circumference of the valve bore 6. Opposite portions of the sleeves are cut away, forming valve heads 8, 9, 10 and 11 extending slightly more than 180° about the valve shaft 7. In this manner, the ports controlled by said heads are opened to alternate inlet and exhaust ports during slightly less than one-half of a revolution of the valve shaft and are closed to alternate inlet and exhaust ports during slightly greater than one-half of a revolution of said shaft, as is more fully described hereinafter. The ends of the valve shaft are of reduced diameter, the forward end thereof being journaled in bearing 12 held in place at the forward stepped end of the valve bore by means of a screw cap 13 threaded to the end of said bore. The rearward end of said valve shaft is mounted in a similar bearing 14 secured in the rear end of the valve bore by means of the screw cap 15 similarly threaded to the end of the valve

bore. The rear end of the valve shaft, however, is extended through the screw cap and is keyed to the rotor 16 of a conventional air motor confined within the housing 17 secured to the rear end of the body 1. It is readily apparent that, by simply removing the screw cap 13 and bearing 12, the entire valve assembly may be withdrawn from the valve bore, as for purposes of repair.

Air is supplied to the valve bore between the spaced valves from a compressed air supply (not shown) through the external conduit 18 secured to the front of the body 1 in communication with the main internal duct 19. Branch lines 20 from the main duct lead to the outer walls of the body 1, and terminate in external air ports 21 adjacent the ends of the forward hammers. Other branch lines 22 extend from the central portion of the valve bore and terminate in air ports 23 adjacent the ends of the rearward hammers. These air ports 21 and 23 are employed to direct jets of compressed air upon the areas of the rollers being subjected to the hammering action, to aid in removing the matter adhering to the rollers. The air line 24 extends rearwardly from the valve bore to the space between the rotor 16 and the housing 17 of the air motor to supply the air required to operate the motor.

Projecting outwardly from the valve bore adjacent the valve heads are air intake ducts 25 and 26 communicating through upper ducts 27 with the ends of the upper forward cylinder, and through lower ducts 28 with the ends of the lower forward cylinder, as best shown in Figs. 6 and 7 of the drawings. Cut-off valves 29 are provided in the lower ducts 28 to permit the inactivation of the lower hammers when the device is to be used on single spaced rollers. Intake ducts 30 and 31 similarly conduct air to upper and lower ducts and cut-off valves in the upper and lower cylinders are disposed at the rear of the body 1. Extending transversely through the end portions of the valve bore and communicating with the outer walls of the body are exhaust ports 32 and 33 for permitting escape of air released from one side of the pistons 4 during the operation of the device, as is more fully explained hereinafter.

A mounting member 34 is secured to or formed in, the top of the body 1. A slot 35 is formed in said mounting member extending longitudinally of said body, and a portion of the exposed face of said member is cut away to form a recess 36 as is best shown in Fig. 2. A swivel head 37 is detachably mounted upon said mounting member by means of a shouldered lug 38 depending from said head and extending through the cut away portion of the mounting member. A retractible key 39 mounted on the swivel head engages one of the holes 40 formed in the mounting member positively to lock the head thereto in the position desired. Extending outwardly from the swivel head are arms 41 by means of which the device is suspended between the rollers to be cleaned. Rollers 42 are rotatably secured to the free ends of said arms to rest upon the rollers to be cleaned, and thereby provide for easy movement of the cleaning device. Bumper bars 43 extend laterally from the body 1 between the upper hammers and are made adjustable in order to accommodate various distances between rollers. These bumpers are adjusted, as shown in Fig. 6, to prevent excessive lateral movement of the cleaning device between the rollers to be cleaned.

Figs. 4 and 5 of the drawings show the clean-

ing device of the present invention mounted for operation between two pairs of cooperating rollers 44 forming a section of a conventional veneer dryer. Such rollers are usually mounted at their ends in spaced upright brackets 45 secured to the dryer frame 46. In installing the cleaning device upon the rollers, the operator first releases the key 39 and rotates the swivel head to position the arms 41 along the longitudinal axis of the body 1, as is shown in Fig. 4. The device is then lifted into position between the rollers 44 and the arms 41 are swung about to rest upon the rollers, as shown in Figs. 5 and 6. The device, thus suspended, is in readiness to be manipulated along the rollers during the cleaning operation.

In operation, compressed air is admitted through the conduit 18 by means of which the cleaning devices are manipulated as they move along the rollers. High pressure air is introduced in the valve bore 6 between the spaced valves and thence to the air motor, the rotor of which is caused to rotate as the air impinges upon the rotor vanes, thus imparting rotation to the valve shaft 7. As is illustrated in Figs. 6 and 7 of the drawings, valve heads 8 and 11 are in position to admit compressed air from the central portion of the valve bore to intake ports 25 and 31, respectively. At the same time, valve heads 9 and 10 seal off intake ports 26 and 30, respectively, from the high pressure air and place these ports in communication with the exhaust ports 32 and 33, respectively. Thus, the forward pistons are caused to move toward the right, in Fig. 7, and the rearward pistons are caused to move to the left. As the front pistons move toward the right, air entrapped on the sides of the pistons flows through ducts 27 and 28 on the right side, through duct 26 into the front end portion of the valve bore, and is exhausted to the atmosphere through port 32. Similarly, air entrapped on the left side of the rear pistons flows through duct 30 into the rear end portion of the valve bore and is exhausted through duct 33.

With the valve shaft rotated to a position 180° from that shown in Figs. 6 and 7, compressed air is admitted to the right side of the forward cylinders through intake port 26, and to the left side of the rearward cylinders through intake port 30. As the forward pistons move to the left, air entrapped on the left side from the previous half-cycle is exhausted through ports 25 and 32. Likewise, as the rearward pistons move toward the right, air entrapped on that side is exhausted through ports 31 and 33.

As the pistons move from one side of the cylinders to the other, the ends of the piston rods strike the rollers upon which the hardened encrusting matter 47 adheres. The sudden jarring effect induced by the hammering of the piston rods upon the rollers loosens the encrusting matter therefrom and, with the aid of the strong jets of air issuing from the ports 21 and 23, is completely removed. The operator merely moves the device longitudinally through the space between the rotating rollers until the latter are thoroughly cleaned. As stated hereinbefore, if the device is to be used upon single spaced rollers, the lower hammers may be inactivated by closing the lower intake ports by means of the cut-off valves 29.

I claim:

1. A device for cleaning rollers comprising, an elongated body having transversely arranged cylinders therein, said elongated body being posi-

tionable so that each transverse cylinder lies between two opposed rollers which are to be cleaned, a reciprocable piston operatively carried in each transverse cylinder, piston rods on said pistons extending through the sides of said body for intermittently contacting the rollers to be cleaned, valve means connecting said cylinders and a source of fluid pressure for reciprocating said pistons, swivel means detachably mounted on said body, and arms extending from said swivel means for movably suspending said cleaning device upon the rollers to be cleaned.

2. A pneumatic device for cleaning rollers comprising, a body, a cylinder in said body, a reciprocating piston in said cylinder, piston rod means on said piston extending through the sides of said body intermittently for contacting the rollers to be cleaned, valve means connecting said cylinder and a supply port to reciprocate said piston, and duct means continuously open to said supply port for directing a stream of compressed air adjacent the free ends of said piston rod to aid the cleaning action of said piston rod and roller contact.

3. A device for cleaning rollers comprising, a body, cylinders in said body, a reciprocating piston in each cylinder, piston rods on said pistons for intermittently contacting the rollers to be cleaned, a valve bore in said body, a duct connecting said valve bore with a source of fluid pressure, ducts connecting said valve bore with said cylinders on opposite sides of said pistons, exhaust ducts connecting said valve bore and the ends of said cylinders with the outside atmosphere, a valve shaft in said bore, a motor for driving said shaft, valves on said shaft cooperating with said cylinder-connecting ducts for alternately admitting and releasing fluid pressure in said cylinders for reciprocating said pistons, swivel means detachably mounted on said body, and arms extending from said swivel means for movably suspending said cleaning device upon the rollers to be cleaned.

4. A pneumatic device for cleaning rollers comprising, a body, cylinders in said body, a reciprocating piston in each cylinder, piston rod means on said pistons extending transversely through the sides of said body for intermittently contacting the rollers to be cleaned, a valve bore in said body, ducts connecting said valve bore with a compressed air supply port and with said cylinders on opposite sides of said pistons and with an exhaust port, a valve shaft in said bore, mounted for rotation, motor means connected to said supply port for rotating said shaft, valve means on said shaft cooperating with said ducts for alternately admitting and releasing compressed air in said cylinders for reciprocating said pistons, and ducts in said body directing

compressed air adjacent the free ends of said piston rods for aiding in the cleaning of said rollers.

5. A device for cleaning rollers comprising, a body, cylinders in said body, a reciprocating piston in each cylinder, piston rod means on said pistons for intermittently contacting the rollers to be cleaned, valve means connecting said cylinders and a compressed air supply port for reciprocating said pistons, means directing compressed air adjacent the free ends of said piston rods for aiding in the cleaning of said rollers, bumper means on said body adjustably positioning the device between spaced rollers to be cleaned, swivel means detachably mounted on said body, and arms extending from said swivel means for movably suspending said cleaning device upon the rollers to be cleaned.
- 20 6. A pneumatic device for cleaning rollers comprising, a body, cylinders in said body, a reciprocating piston in each cylinder, piston rod means on said pistons extending through the sides of said body for intermittently contacting the rollers to be cleaned, a valve bore in said body extending longitudinally thereof, means connecting said valve bore with a compressed air supply port, ducts connecting said valve bore with said cylinders on opposite sides of said pistons, cut-off valves in said ducts for selectively inactivating
- 25 30 35 40 said pistons, exhaust means connecting said valve bore with an exhaust port, valve means mounted in said bore and cooperating with said cylinder-connecting ducts for alternately admitting and releasing compressed air in said cylinders for reciprocating said pistons, ducts in said body directing compressed air adjacent the free ends of said piston rods for aiding in the cleaning of said rollers, bumper means on said body adjustably positioning the device between spaced rollers to be cleaned, swivel means detachably mounted on said body, and arms extending from said swivel means for movably suspending said cleaning device upon the rollers to be cleaned.
